CLAIM

The ornamental design for a micro reflex sight, as shown and described.

DESCRIPTION

FIG. 1 is a front view of the micro reflex sight of our new design:

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a top left perspective view thereof;

FIG. 8 is a bottom, left and front perspective view thereof;

FIG. 9 is a top, right and front perspective view thereof; and,

FIG. 10 is a bottom, right and front perspective view thereof.

1 Claim, 7 Drawing Sheets
